UNITED STATES PATENT OFFICE.

WILLIAM MORRISON, OF TROY, NEW YORK.

BRUSH.

Application filed September 1, 1920. Serial No. 407,303.

To all whom it may concern:

Be it known that I, WILLIAM MORRISON, a citizen of the United States, and resident of Troy, in the county of Rensselaer and State 5 of New York, have invented certain new and useful Improvements in a Brush, of which the following is a full, clear, and exact specification.

This invention relates to a class of brush- 10 ing devices, and has for its object primarily to provide a back of a type whereby a plate of cementitious material with bristles will be held to the back against accidental dis- placement to enable hair brushes, clothes 15 brushes and the like to be manufactured for being sold at moderate prices, and which may be made especially of forms represent- ing expensive brushes with ornamental backs 20 of metal and other sheet material. The in- vention resides mainly in the provision of a back made of sheet metal or other sheet material which is stamped or pressed to pro- vide in one of its faces a recess. On the bot- 25 tom of the recess is a retainer which may be in the form of a band of round wire soldered or otherwise fastened on the plate to pro- 30 vide one or more spaced annular grooves, and on the wall of the recess are spaced clips preferably in the forms of strips or flanges 35 which overhang the edge of the plate inter- 40 niorly of the recess in spaced relation to its wall to provide spaced grooves on the wall. The plate of cementitious material with bris- 45 tles is secured to the back by the retainers 50 and clips being embedded in the plate which is applied in plastic state in the recess of the back so that the material enters the 55 grooves of the back.

A further object of the invention is to 40 provide a brush of a simple and efficient con- struction which may be made in any suitable size and shape.

With these and other objects in view, the invention will be hereinafter more particu- 45 larly described with reference to the accom- panying drawing forming a part of this specification in which similar characters of reference indicate corresponding parts in all the views, and will then be pointed out in 50 the claims at the end of the description.

In the drawing, Figure 1 is an inverted plan of the back adapted to be employed for making one form of my improved brush.

Fig. 2 is a sectional view, partly in detail, 55 taken on the line 2—2 of Fig. 1, and

Fig. 3 is a transverse section, partly in

detail, taken through one form of the com- plete brush.

The brush has a back 10 which may be of any suitable shape and size, though the form 60 of the back illustrated is substantially oval, and the back may be made of sheet metal, celluloid or other appropriate sheet mate- rial. This brush being designed to repre- 65 sent expensive ornamental metal back brushes I preferably make the back 10 of sheet metal which is cut into a plate of the desired shape and then stamped or other- wise formed with a recess or concavity 11 in one of its faces by bending or curving the 70 edge of the plate to provide a wall, as 12. The face of the plate opposite to the recess 11 may be fancifully embossed or ornamented if desired.

On the bottom of the recess 11 of the 75 back in spaced relation to the wall 12 is a retainer 13 which may consist of a circu- 80 lar or oval shaped band or ring of round wire being soldered or otherwise fastened to the bottom of the recess. By making the 85 retainer or band of round metal wire and by properly soldering it to the back the spaces between the back and the wire at both of its lengthwise sides provide spaced annular 90 grooves, as 14 and 15.

Interiorly of the recess 11 of the back and 95 on the free edge of the wall 12 may be one or a number of spaced clips, as 16. These clips are preferably of similar formations, and each clip may be in the form of a strip or 100 flange of metal. The clips or strips are ar- ranged lengthwise of the wall 12 of the back, and one edge of each strip is soldered or otherwise secured to the free edge of the wall so that all of the strips are disposed on inclines toward the center of the recess in spaced relation to the wall to provide a 105 groove, as 17, between each strip and the wall of the recess. The grooves 14, 15, 17 are thereby in communication with the recess.

The form of brush provided by the em- 110 ployment of this back consists of a plate, as 18, of cementitious material of any well known or preferred formula, and the bris- tles 19 of the brush are embedded in the plate so as to protrude therefrom. The plate when formed and while in a state of plasticity is pressed into the recess 11 of the back, and by exercising sufficient pressure the material of the plate will be caused to enter the grooves 14, 15, 17 as well as caus- 115 ing the retainer 13 and clips 16 to be em-

bedded in the plate. Thus I provide a brush which is susceptible of being made in ornamental and very attractive designs as well as being made to sell at a moderate price.

5 In the foregoing description, I have embodied the preferred form of my invention, but I do not wish to be understood as limiting myself thereto, as I am aware that modifications may be made therein without

10 departing from the principle or sacrificing any of the advantages of this invention, therefore I reserve to myself the right to make such changes as fairly fall within the scope thereof.

15 Having thus described my invention, I

claim as new and desire to secure by Letters Patent:—

In a brush, a recessed metal back, and metal anchor strips protruding into the recess of the back from spaced parts of the edge portion of the wall of the recess for being embedded in a bristle carrying plate of cementitious material when provided in the recess of the back. 20

This specification signed and witnessed 25
this 31st day of August, A. D. 1920.

WILLIAM MORRISON.
